EUGENE C. HERTHEL, OF CHICAGO, ILLINOIS, ASSIGNOR TO SINCLAIR REFINING COMPANY, OF NEW YORK, N. Y., A CORPORATION OF MAINE

ART OF CRACKING HYDROCARBONS

Application filed March 7, 1929. Serial No. 345,199.

This invention relates to improvements in the combined vapor phase cracking of oils, such as gas oil or kerosene stocks, for the production of lower boiling oils, such as gaso-line, and the coking of heavy oils, such as crudes, topped crudes, flux oils, other residual oils and the like. The combined operation of the invention is of special application in the handling of crude stocks or residual stocks the handling of which usually involves difficulties due to corrosion or the products of which are usually refractory with respect to the usual refining operations, because of the character or quantity of sulphur com- pounds in the stock, for example; but, as will appear, the invention is, in certain aspects, of more general application.

The invention is of special application in conjunction with the combined vapor phase cracking and coking operations claimed in application Serial No. 340,996 filed February 18 1929, by Harry L. Pelzer.

The invention also includes an improved apparatus of special value in carrying out the invention.

In carrying out coking operations in which the stock to be reduced to coke is coked by direct heat exchange with the hot vapor mixture discharged from a vapor phase cracking operation, as in the operations described in application Serial No. 340,996, mentioned above, for example, the stock supplied to the coking operation proper is advantageously supplied to the coking operation as a stock which has been reduced to a gravity approximating 15 degrees A. P. I. or heavier. In carrying out vapor phase cracking operations for the production of gasoline in which the stock supplied to the vapor phase cracking operations is heated to temperatures of 950-1150° F., for example, the stock supplied to the vapor phase cracking operation proper is advantageously supplied to the vapor phase cracking operation as a stock having a carbon residue content as determined by the United Gas Improvement Company gas oil distillation test not exceeding about 0.3%. This gas oil distillation test is well known to the art as, and is hereinafter referred to as, the U. G. I. gas oil distillation test.

This invention provides an improved method of operation, or an improved method of controlling such operations, which simplifies the conjoint meeting of these two requirements, which tend to be in opposition, in combined vapor phase cracking and coking operations such as those claimed in application Serial No. 340,996, mentioned above.

According to the present invention, an oil stock having a carbon residue content as determined by the U. G. I. gas oil distillation test not exceeding about 0.3% is subjected to a vapor phase cracking operation, the hot vapor mixture from the vapor phase cracking operation is supplied to a coking operation in which a liquid oil mixture is coked by direct heat exchange with this hot vapor mixture, the hot vapor mixture from the coking operation is discharged into and beneath the surface of a liquid body of oil maintained in the lower end of a baffled tower, the raw oil stock to be reduced to coke is introduced into the lower end of the baffled tower to mingle with this liquid body of oil and the resulting oil mixture is supplied from this liquid body of oil to the coking operation, the vapors escaping from the upper end of the baffled tower are subjected to a fractionating operation, the vapors escaping from the fractionating operation are condensed to form a distillate product, condensate separated from the vapors in the fractionating operation is supplied to the vapor phase cracking operation, and a refluxing medium is supplied to the upper end of the baffled tower at a rate regulated to maintain the gravity of the oil mixture supplied from the liquid body of oil in the lower end of the baffled tower to the coking operation within the desired gravity range, say, 5-15 A. P. I. By supplying the raw oil stock to be reduced to coke directly to the liquid body of oil in the lower end of the baffled tower, the formation of coke in this tower is inhibited and, in conjunction with the supply of a refluxing medium to the upper end of the baffled tower, the carrying over into the fractionating operation of components increasing the U. G. I. coke content of condensates separated from the vapors in the

fractionating operation is minimized. By supplying the raw oil stock to be reduced to coke to the liquid body of oil in the lower end of the baffled tower and by supplying a 5 separate refluxing medium to the upper end of the baffled tower, regulation of the baffled tower operation, in which lower boiling components are separated from the raw stock to be reduced to coke, is made substantially independent of the rate at which this raw oil 10 stock to be reduced to coke is supplied, making it possible to regulate this latter rate primarily with reference to the coking operation proper. Condensate separated from 15 the vapors in the fractionating operation may, with advantage, be introduced into the upper end of the baffled tower as a refluxing medium; or the raw oil stock to be reduced to coke may, with advantage, be passed in direct 20 heat exchanging relation with the vapors escaping from the upper end of the baffled tower before this stock is introduced into the lower end of the baffled tower and the condensate so produced supplied to the 25 baffled tower as a refluxing medium; or both of these refluxing media may be supplied to the baffled tower and the rates at which they are supplied conjointly regulated.

The invention will be further described in 30 connection with the accompanying drawings which illustrate, diagrammatically and conventionally, one form of apparatus, in elevation and partly in section with parts broken away, adapted for carrying out the 35 invention, but it is intended and will be understood that the invention can be carried out in other and different forms of apparatus and that this further description is intended as exemplification of the invention. The 40 accompanying drawings also illustrate a tower which, in combination with the vapor phase cracking apparatus and the coking apparatus illustrated, embodies another aspect of the invention.

45 In carrying out the invention in the apparatus illustrated, an oil stock having a carbon residue content as determined by the U. G. I. gas oil distillation test not exceeding about 0.3% is supplied through connection 1 to the vapor phase cracking heater 2, this stock is subjected to a vapor phase cracking operation in the vapor phase cracking heater 2, the hot vapor mixture from the vapor phase cracking operation, without substantial cooling, is introduced into the coking receptacle 3 in which it is passed in intimate contact with a liquid oil mixture to be coked supplied from a liquid oil body maintained in the lower end of the baffled 55 tower 4 through connection 5 by means of hot oil pump 6 and this oil mixture is thereby coked in the coking receptacle 3, the hot vapor mixture from the coking receptacle is discharged into and beneath the surface of the 60 liquid body of oil maintained in the lower 65

end of tower 4 through connections 7 and 8, the oil stock to be coked is introduced into the liquid body of oil maintained in the lower end of tower 4 through connection 9, the vapor mixture from the upper end of tower 4 is discharged through dephlegmators 10 and 11 into the lower end of fractionating tower 12, the vapor mixture from the upper end of tower 12 is discharged through dephlegmator 13 either to the condenser 14 70 or through the fractionating tower 15 and the dephlegmator 16 to the condenser 14, and a coke product is periodically discharged from the coking receptacle 3. Condenser 14 is arranged to discharge into receiver 17 from 80 which the condensate product is discharged through connections 18 and 19 and from which uncondensed vapors and gases are discharged through connection 20.

The hot oil pump 6, as well as the hot oil 85 pumps 21 and 22, may, with advantage, be of the type described and illustrated in Patent No. 1,701,198 issued February 5, 1929, to the Sinclair Refining Company, on the application of Thomas de Colon Tift.

The vapor phase cracking operation proper may be carried out, for example, as described in application Serial No. 198,621 filed June 13, 1927, by Harry L. Pelzer, and the hot vapor mixture from the digesting drums 95 discharged directly into the coking receptacle, or the digesting drums may be omitted and the hot vapor mixture from the heater proper may be discharged directly into the coking receptacle, as in the apparatus illustrated.

100 Connections 23, 24 and 25 are provided for supplying steam to the heater 2, to the lower end of the coking receptacle 3, and to the lower end of the baffled tower 4, respectively. Condenser 26 is provided for use in steaming out the coking receptacle 3. Connection 30 is provided for by-passing the coking receptacle 3 while discharging coke charges from and while cleaning this receptacle.

110 The type of baffled tower 4 illustrated is of special value in carrying out the invention. This tower comprises three parts; a lower part adapted for the maintenance of a liquid body of oil to which the raw stock to be coked is supplied through connection 9, into which the hot vapor mixture from the coking operation proper is discharged through a submerged inlet connection 8, and from which the oil mixture supplied to the coking operation proper is withdrawn through connection 26; an intermediate part provided with open plate baffles 27 adapted for providing limited fractionation with a minimum danger of obstruction through accumulations of heavy oil 115 or semi-solid coke material; and an upper part provided with "bubble plates" 28 or other equivalent baffling means adapted for providing relatively close fractionation. The baffled tower 4 is, with advantage, lagged or thermal- 120 125 130

ly insulated. A refluxing medium may be introduced into the upper end of the baffled tower 4 through connection 29, or a refluxing medium may be supplied to the upper end of 5 baffled tower 4 from either or both of the dephlegmators 10 and 11, or refluxing media may be supplied in both ways at the same time. Dephlegmator 10 is provided with coils through which the oil stock to be coked, or 10 part of it, may be passed in indirect heat exchanging relation with the vapors escaping from the upper end of the baffled tower 4 before introduction into the lower end of the baffled tower 4 through connection 9. This 15 oil stock is supplied by means of pump 31 through connection 32. The operation of the dephlegmator 10 may be controlled, for example, by regulated by-passing of this oil stock through connection 33. Dephlegmator 20 11 is provided with coils through which water or some other extraneous cooling medium may be circulated. The several refluxing means provided may be used conjointly or separately, and if used separately those not used may 25 be omitted as part of the apparatus. The dephlegmator 11 may be used, for example, to supplement the refluxing action either of a refluxing medium introduced through connection 29 or of the dephlegmator 10. Any 30 excess of the oil mixture accumulating in the lower end of the tower 4 may be discharged through connection 34 and cooler 35. The condensate or part of the condensate produced in the fractionating tower 12, or the con- 35 densate or part of the condensate produced in the fractionating tower 15, or a mixture of these condensates, may be supplied to the upper end of the baffled tower 4 through connection 29 as a refluxing medium, either through 40 connection 36 or, and usually more advantageously, through cooler 37, by means of either or both of the pumps 21 and 22 and the connections illustrated.

Condensate produced in the fractionating 45 tower 12 or condensate produced in the fractionating tower 15 or a mixture of these condensates is supplied to the vapor phase cracking heater 2 through connections 38 and 1 by means of the pump 21 or the pump 22 or 50 both of these pumps. Additional raw stock may also be supplied to the cracking heater 2 through connections 39 and 1 by means of pump 40. When the vapor mixture from the baffled tower 4 is passed successively through 55 the fractionating towers 12 and 15, the U. G. I. carbon residue test of the condensate from the fractionating tower 12 is normally higher than that of the condensate from the fractionating tower 15, and the U. G. I. carbon 60 residue test of the stock supplied to the vapor phase cracking operation, may be controlled by regulating the proportion of these condensates supplied to the vapor phase cracking operation in a mixture of the two; for example, to decrease the U. G. I. carbon residue

test of the stock supplied to the vapor phase cracking operation, where a condensate or a condensate mixture produced in the fractionating operation also is used as a refluxing medium in the baffled tower 4, the proportion of the condensate from the fractionating 70 tower 12 in a condensate mixture used as a refluxing medium in the tower 4 may be increased and the proportion of the condensate from the fractionating tower 15 in a condensate mixture supplied to the vapor phase 75 cracking operation increased. The U. G. I. carbon residue test of the stock supplied to the vapor phase cracking operation may also be limited, for example, by the supplemental introduction of a raw stock of relatively low 80 U. G. I. carbon residue test through connection 39. When the U. G. I. carbon residue test of the condensate mixture supplied to the vapor phase cracking operation from the fractionating operation is relatively low, a raw stock of relatively high U. G. I. carbon residue test may be introduced through connection 39 in amount limited so that the U. G. I. carbon test of the resulting stock 85 mixture does not exceed the desired limit. The fractionating towers 12 and 15 may be of any conventional type, the so-called "bubble plate" type for example, adapted for providing close fractionation. The operation of 90 these fractionating towers may be controlled by the regulated introduction of refluxing media through connections 41 and 42, or by means of the dephlegmators 13 and 16, or by both of these means conjointly. Dephlegmators 13 and 16 are provided with coils 95 through which water or some other extraneous cooling medium may be circulated. Part of the condensate produced in the fractionating tower 15 may be supplied to the upper end of the fractionating tower 12 as a refluxing medium, or some similar fraction 100 may be so supplied to the upper end of the fractionating tower 12 as a refluxing medium. Part of the condensate product may be supplied to the upper end of the tower 15 as a refluxing medium, or some similar fraction 105 may be so supplied to the upper end of the fractionating tower 15 as a refluxing medium, through connection 42 by means of pump 43. Any excess condensates produced in the fractionating tower 12 or 15 may be discharged through connection 44 and cooler 45 or through connection 46 and cooler 47, respectively. Connection 48 is provided for 110 by-passing the fractionating tower 15.

The invention will be further illustrated by the following examples of operations embodying the invention as carried out in apparatus of the type illustrated:

The operation of the vapor phase cracking heater 2 and the coking receptacle 3 being carried out as described in application Serial No. 340,996, mentioned above, reduced crude is introduced into the lower end of 125 130

baffled tower 4 at a fixed rate approximating 200 gallons per hour and a gas oil condensate produced in the fractionating tower 12 is introduced into the upper end of the baffled tower 4 through connection 29 at a rate approximating 250 gallons per hour regulated to maintain the gravity of the residual stock mixture pumped through connection 5 to the coking receptacle close to 10 A. P. I. The fractionating tower 12 is operated to produce a heavy gas oil reflux condensate and the operation of the fractionating tower 15 is regulated so that the condensate produced from the vapors escaping from the fractionating tower 15 is a gasoline of the desired boiling range, say, 410° F. end-point. The stock mixture produced by adding the condensate produced in the fractionating tower 15 to that part of the condensate produced in the fractionating tower 12 not supplied to the baffled tower 4 as a refluxing medium has a U. G. I. carbon residue test not exceeding 0.3% and is supplied to the vapor phase cracking heater 2.

Comparing the operation just outlined to an operation in which no refluxing medium is supplied to the upper end of the baffled tower 4, approximately 400 gallons per hour of reduced crude may be supplied to the baffled tower 4 to maintain the residual stock mixture of the desired gravity and the U. G. I. carbon residue test of the condensate produced in the fractionating tower 12, under these conditions, may be as high as 2.0% or higher. Further, the operation embodying the invention is free from difficulty due to the formation of coke in the baffled tower 4.

The operation of the vapor phase cracking heater 2 and the coking receptacle 3 being carried out as described in application Serial No. 340,996, mentioned above, reduced crude is pumped through the coils in the dephlegmator 10 and then introduced into the lower end of the baffled tower 4, all of the reduced crude being passed through the coils in the dephlegmator 10, at a rate approximating 250-300 gallons per hour and the operation of the dephlegmator 11 is controlled to maintain the gravity of the residual stock mixture pumped from the lower end of the baffled tower 4 to the coking receptacle 3 through connection 5 close to 10 A. P. I. The vapors from the fractionating tower 12 are passed directly to the condenser and the operation of this fractionating tower is controlled so that the condensate produced in the condenser is a gasoline product of the desired boiling range, say, 410° F. end-point. The condensate produced in the fractionating tower 12 is of U. G. I. carbon residue test not exceeding 0.3% and is supplied to the vapor phase cracking heater.

The type of baffled tower illustrated in the accompanying drawings, the baffled tower 4, is of special value in combination with cok-

ing apparatus in which the heat for coking is internally supplied by the direct introduction of the hot vapor mixture from a vapor phase cracking operation, for the production of a clean, or substantially clean, vapor fraction. With a tower of the type illustrated, operated as previously described, it is possible to produce residual stock mixtures containing as little as 1% boiling off below 600° F. at atmospheric pressure and at the same time to produce a condensate from the escaping vapor fraction, including the highest boiling components of the escaping vapor fraction, with an end boiling point as low as 580° F. at atmospheric pressure. Using an ordinary open baffled tower in this operation, it is not unusual for the residual stock mixture to contain as much as 40% boiling off below 600° F. and for the vapor fraction to include components having boiling points as high as 700° F. or higher.

I claim:

1. In a combined vapor phase cracking and coking operation, the improvement which comprises subjecting oil stock having a carbon residue content as determined by the U. G. I. gas oil distillation test not exceeding about 0.3% to a vapor phase cracking operation, subjecting a liquid oil mixture to a coking operation in which said oil mixture is coked by direct heat exchange with the hot vapor mixture from the vapor phase cracking operation, discharging the hot vapor mixture from the coking operation into and beneath the surface of a liquid body of oil maintained in the lower end of a baffled tower subjecting the vapors to a refluxing operation in said baffled tower, introducing the raw oil stock to be coked into the lower end of the baffled tower to mingle with said liquid body of oil therein and supplying the resulting composite oil mixture from said liquid body of oil including condensate formed in said refluxing operation to the coking operation, subjecting the vapors escaping from the upper end of the baffled tower to a fractionating operation, discharging vapors escaping from the fractionating operation to a condenser and condensing a distillate product therein, introducing condensate separated from the vapors in the fractionating operation into the upper end of the baffled tower as a refluxing medium, and supplying condensate separated from the vapors in the fractionating operation to the vapor phase cracking operation.

2. In a combined vapor phase cracking and coking operation, the improvement which comprises subjecting oil stock having a carbon residue content as determined by the U. G. I. gas oil distillation test not exceeding about 0.3% to a vapor phase cracking operation, subjecting a liquid oil mixture to a coking operation in which said oil mixture is coked by direct heat exchange with the

hot vapor mixture from the vapor phase cracking operation, discharging the hot vapor mixture from the coking operation into and beneath the surface of a liquid body of oil maintained in the lower end of a baffled tower, subjecting the vapors to a refluxing operation in said baffled tower, introducing the raw oil stock to be coked into the lower end of the baffled tower to mingle with said liquid body of oil therein and supplying the resulting composite oil mixture from said liquid body of oil including condensate formed in said refluxing operation to the coking operation, subjecting the vapors escaping from the upper end of the baffled tower to a fractionating operation, discharging vapors escaping from the fractionating operation to a condenser and condensing a distillate product therein, introducing condensate separated from the vapors in the fractionating operation into the upper end of the baffled tower as a refluxing medium, regulating the introduction of said refluxing medium to maintain the oil mixture supplied from said liquid oil body in the baffled tower to the coking operation of gravity not substantially exceeding 15 degrees A. P. I. and supplying condensate separated from the vapors in the fractionating operation to the vapor phase cracking operation.

vapors in the fractionating operation to the vapor phase cracking operation.

4. In a combined vapor phase cracking and coking operation, the improvement which comprises subjecting oil stock having a carbon residue content as determined by the U. G. I. gas oil distillation test not exceeding about 0.3% to a vapor phase cracking operation, subjecting a liquid oil mixture to a coking operation in which said oil mixture is coked by direct heat exchange with the hot vapor mixture from the vapor phase cracking operation, discharging the hot vapor mixture from the coking operation into and beneath the surface of a liquid body of oil maintained in the lower end of a baffled tower, subjecting the vapors to a refluxing operation in said baffled tower, introducing the raw oil stock to be coked into the lower end of the baffled tower to mingle with said liquid body of oil therein and supplying the resulting composite oil mixture from said liquid body of oil including condensate formed in said refluxing operation to the coking operation, subjecting the vapors escaping from the upper end of the baffled tower to a fractionating operation, discharging vapors escaping from the fractionating operation to a condenser, passing raw oil stock to be coked in indirect heat exchanging relation with the vapors escaping from the upper end of the baffled tower before introduction into the lower end of the baffled tower and supplying condensate produced from the vapors by the cooling action of the raw oil stock to the baffled tower as a refluxing medium, regulating the supply of said refluxing medium to maintain the oil mixture supplied from said liquid body of oil in the baffled tower to the coking operation of gravity not substantially exceeding 15 degrees A. P. I.

3. In a combined vapor phase cracking and coking operation, the improvement which comprises subjecting oil stock having a carbon residue content as determined by the U. G. I. gas oil distillation test not exceeding about 0.3% to a vapor phase cracking operation, subjecting a liquid oil mixture to a coking operation in which said oil mixture is coked by direct heat exchange with the hot vapor mixture from the vapor phase cracking operation, discharging the hot vapor mixture from the coking operation into and beneath the surface of a liquid body of oil maintained in the lower end of a baffled tower, subjecting the vapors to a refluxing operation in said baffled tower, introducing the raw oil stock to be coked into the lower end of the baffled tower to mingle with said liquid body of oil therein and supplying the resulting composite oil mixture from said liquid body of oil including condensate formed in said refluxing operation to the coking operation, subjecting the vapors escaping from the upper end of the baffled tower to a fractionating operation, discharging vapors escaping from the fractionating operation to a condenser, passing raw oil stock to be coked in indirect heat exchanging relation with the vapors escaping from the upper end of the baffled tower before introduction into the lower end of the baffled tower and supplying condensate produced from the vapors by the cooling action of the raw oil stock to the baffled tower as a refluxing medium, regulating the supply of said refluxing medium to maintain the oil mixture supplied from said liquid body of oil in the baffled tower to the coking operation of gravity not substantially exceeding 15 degrees A. P. I.

5. In a combined vapor phase cracking and coking operation, the improvement which comprises subjecting oil stock having a carbon residue content as determined by the U. G. I. gas oil distillation test not exceeding about 0.3% to a vapor phase cracking operation, subjecting a liquid oil mixture to a coking operation in which said oil mixture is coked by direct heat exchange with the hot vapor mixture from the vapor phase cracking operation, discharging the hot vapor mixture from the coking operation into and beneath the surface of a liquid body of oil maintained in the lower end of a baffled tower, subjecting the vapors to a refluxing operation in said baffled tower, introducing the raw oil stock to be coked into the lower end of the baffled tower to mingle with said liquid body of oil therein and supplying the resulting composite oil mixture from said liquid body of oil including condensate formed in said refluxing operation to the coking operation, subjecting the vapors escaping from the upper end of the baffled tower to a fractionating operation, discharging vapors escaping from the fractionating operation to a condenser, passing raw oil stock to be coked in indirect heat exchanging relation with the vapors escaping from the upper end of the baffled tower before introduction into the lower end of the baffled tower and supplying condensate produced from the vapors by the cooling action of the raw oil stock to the baffled tower as a refluxing medium, regulating the supply of said refluxing medium to maintain the oil mixture supplied from said liquid body of oil in the baffled tower to the coking operation of gravity not substantially exceeding 15 degrees A. P. I.

from the upper end of the baffle tower to a fractionating operation, discharging vapors escaping from the fractionating operation to a condenser and condensing a distillate product therein, introducing condensate separated from the vapors in the fractionating operation into the upper end of the baffled tower as a refluxing medium, passing raw oil stock to be coked in indirect heat exchange relation with the vapors escaping from the upper end of the baffled tower before introduction into the lower end of the baffled tower and supplying condensate so produced to the baffled tower as a refluxing medium.

15 6. In combination in an oil coking apparatus in which heat for coking is internally supplied by the direct introduction of a hot vapor mixture from a vapor-phase cracking operation, a heating conduit, means for supplying oil thereto, means for heating said conduit to a temperature sufficient to effect conversion of the oil therein in the vapor phase, a coking receptacle and a connection from said heating conduit to said coking receptacle, a

20 scrubbing tower comprising a shell, a series of open baffles in the intermediate part, a series of "bubble plates" in the upper part, means for supplying a refluxing medium to the upper part, means for introducing vapors

25 from the coking receptacle into the lower part, and means for introducing a heavy oil to and for intimately contacting said heavy oil and vapors in the lower part, means for supplying liquid oil from the lower part of

30 said scrubbing tower to the coking receptacle, a fractionating tower, means for discharging vapors from the upper part of said scrubbing tower to the fractionating tower, and a connection for returning liquid from the

35 lower part of said fractionating tower to said heating conduit.

7. In a combined vapor-phase cracking and coking operation, the improvement which comprises subjecting oil stock having a carbon residue content as determined by the U. G. I. gas oil distillation test not exceeding about 0.3% to a vapor-phase cracking operation, subjecting a liquid oil mixture to a coking operation in which said oil mixture is coked by direct heat exchange with the hot vapor mixture from the vapor-phase cracking operation, discharging the hot vapor mixture from the coking operation into and beneath the surface of a liquid body of oil

45 maintained in the lower end of a baffled tower, subjecting vapors passing through the baffled tower to a refluxing operation therein, introducing raw oil stock to be coked into the lower end of the baffled tower to mingle with

50 said liquid body of oil therein, supplying the resulting composite oil mixture from said liquid body of oil including condensate formed in said refluxing operation to the coking operation, subjecting the vapors escaping

55 from the upper end of the baffle tower to a

fractionating operation, discharging vapors escaping from the fractionating operation to a condenser and condensing a distillate product therein, controlling the refluxing operation and the fractionating operation so as to separate from the vapors in the fractionating operation a condensate having a carbon residue content as determined by the U. G. I. gas oil distillation test not exceeding about 0.3%, and supplying the condensate thus separated from the vapors in the fractionating operation to the vapor-phase cracking operation.

8. In a combined vapor-phase cracking and coking operation, the improvement which comprises subjecting oil stock having a carbon residue content as determined by the U. G. I. gas oil distillation test not exceeding about 0.3% to a vapor-phase cracking operation, subjecting a liquid oil mixture to a coking operation in which said oil mixture is coked by direct heat exchange with the hot vapor mixture from the vapor-phase cracking operation, discharging the hot vapor mixture from the coking operation into and beneath the surface of a liquid body of oil maintained in the lower end of a baffled tower, subjecting vapors passing through the baffled tower to a refluxing operation therein, introducing raw oil stock to be coked into the lower end of the baffled tower to mingle with said liquid body of oil therein and supplying the resulting composite oil mixture from said liquid body of oil including condensate formed in said refluxing operation to the coking operation, subjecting the vapors escaping from the upper end of the baffled tower to a fractionating operation, discharging the vapors escaping from the fractionating operation to a condenser and condensing a distillate product therein, controlling the refluxing operation and the fractionating operation to maintain the oil mixture supplied from said liquid body in the baffled tower to the coking operation of gravity not substantially exceeding 15° A. P. I., and to separate from the vapors in the fractionating operation a condensate having a carbon residue content as shown by the U. G. I. gas oil distillation test not exceeding about 0.3%, and supplying condensate thus separated from the vapors in the fractionating operation to the vapor-phase cracking operation.

9. In a combined vapor-phase cracking and coking operation, the improvement which comprises subjecting oil stock having a carbon residue content as determined by the U. G. I. gas oil distillation test not exceeding about 0.3% to a vapor-phase cracking operation, subjecting a liquid oil mixture to a coking operation in which said oil mixture is coked by direct heat exchange with the hot vapor mixture from the vapor-phase cracking operation, discharging the hot vapor mixture from the coking operation into

and beneath the surface of a liquid body of oil maintained in the lower end of a baffled tower, passing a liquid cooling medium in heat exchange with the vapors in the upper end of the baffled tower and thereby subjecting the vapors in the baffled tower to a refluxing operation, introducing the raw oil stock to be coked into the lower end of the baffled tower to mingle with said liquid body of oil therein and supplying the resulting composite oil mixture from said liquid body of oil including condensate formed in the refluxing operation to the coking operation, subjecting the vapors escaping from the upper end of the baffled tower to a fractionating operation, discharging vapors escaping from the fractionating operation to a condenser and condensing the distillate product therein, regulating the passage of said cooling medium in heat exchange with the vapors in the upper end of the baffled tower and simultaneously regulating the fractionating operation to maintain the oil mixture supplied from said liquid body in the baffled tower to the coking operation of gravity not exceeding 15° A. P. I., and to separate from the vapors in the fractionating operation a condensate having a carbon residue content as determined by the U. G. I. gas oil distillation test not exceeding about 0.3%, and supplying condensate thus separated from the vapors in the fractionating operation to the vapor-phase cracking operation.

10. In a combined vapor-phase cracking and coking operation, the improvement which comprises subjecting oil stock having a carbon residue content as determined by the U. G. I. gas oil distillation test not exceeding about 0.3% to a vapor-phase cracking operation, subjecting a liquid oil mixture to a coking operation in which said oil mixture is coked by direct heat exchange with the hot vapor mixture from the vapor-phase cracking operation, discharging the hot vapor mixture from the coking operation into the lower end of a baffled tower, subjecting the vapors passing through the baffled tower to a refluxing operation therein, maintaining a body of liquid oil in the lower end of the baffled tower, introducing raw oil stock to be coked into the lower end of the baffled tower so as to mingle with said liquid body of oil therein and intimately contact with the hot vapor mixture discharged from the coking operation, supplying the resulting composite oil mixture from said liquid body of oil including condensate formed in said refluxing operation to the coking operation, subjecting the vapors escaping from the upper end of the baffled tower to a fractionating operation, discharging vapors escaping from the fractionating operation to a condenser and condensing a distillate product therein, controlling the refluxing operation and the fractionating operation so as to maintain the oil mixture supplied to the coking operation from the liquid body in the baffled tower substantially free from oil boiling below about 600° F. at atmospheric pressure and so as to separate from the vapors in the fractionating operation a condensate having an end boiling point of approximately 580° F. at atmospheric pressure, and supplying the condensate thus separated from the vapors in the fractionating operation to the vapor-phase cracking operation.

In testimony whereof I affix my signature.
